US00D649810S

(12) **United States Design Patent**
Martin et al.

(10) **Patent No.:** **US D649,810 S**
(45) **Date of Patent:** **** Dec. 6, 2011**

(54) **PORTION OF A WORKSPACE**

(75) Inventors: **Kirt Martin**, Alto, MI (US); **David Eberlein**, Hudsonville, MI (US)

(73) Assignee: **Steelcase Inc.**, Grand Rapids, MI (US)

(**) Term: **14 Years**

(21) Appl. No.: **29/362,952**

(22) Filed: **Jun. 2, 2010**

(51) **LOC (9) Cl.** **06-06**

(52) **U.S. Cl.** **D6/484; D6/511; D6/495**

(57) **CLAIM**

The ornamental design for a portion of a workspace, as shown and described.

DESCRIPTION

FIG. 1 is a left, top, front perspective view of a portion of a workspace embodying our new design;

FIG. 2 is a top plan view thereof;

FIG. 3 is a left side elevational view thereof;

FIG. 4 is a front elevational view thereof, the rear elevational view thereof being a mirror image of the front view shown;

FIG. 5 is bottom plan view thereof; and,

FIG. 6 is a right side elevational view thereof.

The broken line representations in the figures are for the purpose of illustration only, and form no part of the claimed design.

1 Claim, 4 Drawing Sheets
